UNITED STATES PATENT OFFICE.

MAX SCHNEIDER, OF CHICAGO, ILLINOIS, ASSIGNOR TO NERNST LAMP COMPANY, A CORPORATION OF PENNSYLVANIA.

DESIGN FOR A LIGHT-FIXTURE.

40,302.

Specification for Design. Patented Oct. 12, 1909.

Application filed June 2, 1909. Serial No. 499,824. Term of patent 14 years.

To all whom it may concern:

Be it known that I, MAX SCHNEIDER, a citizen of the United States, residing in Chicago, in the county of Cook and State of Illinois, have invented a new, original, and ornamental Design for Light-Fixtures, of which the following is a specification, reference being had to the accompanying drawing, forming a part thereof.

The figure of the drawing is a perspective view showing the design of the article.

I claim:

The ornamental design for a light fixture, as shown.

MAX SCHNEIDER.
